UNITED STATES PATENT OFFICE.

WILLARD F. RICHARDS, OF DEPEW, NEW YORK, ASSIGNOR TO GOULD COUPLER COMPANY, OF NEW YORK, N. Y.

DRAFT-GEAR.

1,236,872.

Specification of Letters Patent. Patented Aug. 14, 1917.

Application filed March 30, 1915. Serial No. 17,991.

To all whom it may concern:

Be it known that I, WILLARD F. RICHARDS, a citizen of the United States, residing at Depew, in the county of Erie and State of New York, have invented a new and useful Improvement in Draft-Gears, of which the following is a specification.

This invention relates to friction draft gears for railway cars of the kind which 10 act both in drawing and in buffing.

Great difficulties have been experienced in the production of draft gears having the high capacity required for modern railway rolling stock for the reason that while the 15 capacity required of draft gears has greatly increased within recent years, owing to the increase in the size and carrying capacity of cars and locomotives and the corresponding increase in the size of trains, the space on 20 each car available for the draft gears and the length of travel of the coupler in its draft and buffing action has not been altered by the specifications of the Master-Car Builders' Association. Consequently it is 25 necessary to produce a draft gear of very greatly increased capacity which can be confined within a space of the size formerly allotted to gears of much less capacity, while the permissible travel of the movable 30 part of the gear also remains the same as formerly.

The objects of the invention are to produce a draft gear of the size and travel required by the Master Car Builders' Association and which has the capacity required by the railroads for the heavy modern rolling stock; also to improve the construction of parts of the draft gear in such a manner as to enable them to withstand the stresses 40 acting thereon; also to so construct the parts of the draft gear that the area of contact of the coöperating friction faces will be substantially the same in all positions of the parts of the draft gear; also to so construct 45 the draft gear that the parts thereof will be held in the proper operative relation with regard to each other without the necessity for securing means when the draft gear is not in position on the car, to facilitate the 50 handling and shipping of the draft gear; also to improve the construction of draft gears of this kind in the respects hereinafter specified.

In the accompanying drawings:

55 Figure 1 is a sectional-plan view of a

draft gear embodying the invention showing the same in position between the draft sills.

Fig. 2 is a side elevation thereof, showing a part of the draft gear in section.

Figs. 3 and 4 are transverse sectional elevations on lines 3—3 and 4—4, Fig. 1.

Fig. 5 is a perspective view of the rear end of the housing of the draft gear.

Fig. 6 is a perspective view of one of the wedge plates of the draft gear.

Fig. 7 is a sectional plan view of a draft gear of modified construction.

Briefly stated, the draft gear comprises a hollow shell or housing which is open at one end and in which the resistance means of the draft gear are confined. The housing is provided near its open end with inclined friction faces which coöperate with corresponding faces on movable wedge plates in such a manner that when the wedge plates 75 are moved into the housing in the action of the gear, leaf springs interposed between the wedge plates will press the wedge plates forcibly against the friction faces of the housing, thereby creating friction to resist 80 the movement of the wedge plates. A spring, which is located in the housing and acts in a direction lengthwise thereof, serves to return the wedge plates to their initial position after the gear has been acted upon 85 either by drawing or buffing strains.

Referring first to the construction shown in Figs. 1 to 4, inclusive, A represents cheek plates or parts of any usual or suitable construction which are secured to the draft sills 90 of the car and which are provided with inwardly extending stops or shoulders a, between which the draft gear is held. B represents the shell or housing for the draft gear which, in the construction shown, is 95 substantially rectangular in cross section and is open at one end, for instance its rear end, and closed at its opposite end. The housing is provided adjacent to its open end with opposed inwardly converging, inclined 100 friction faces b which are adapted to coöperate with corresponding inclined faces on wedge plates C slidably arranged in the open end of the housing and extending rearwardly beyond the rear ends of the friction 105 faces b. The friction faces on the wedge plates and on the housing are so arranged relatively to each other that the wedge plates will move toward each other when they are driven into the housing by the ac- 110

tion of the draft gear. The movement of the wedge plates toward each other is opposed by leaf springs D, consisting of a plurality of curved plates preferably arranged in two groups with the convexed sides of the groups facing each other and the ends of the groups bearing against the wedge plates C.

The inclined faces of the friction plates 10 extend substantially to the rear ends of the plates, so that when the plates are moved into the housing, the rear portions of the friction faces of the plates which are normally outside of the housing move into engagement with the friction faces of the housing while the inner portions of the friction faces of the plates move out of engagement therewith. By this arrangement, substantially the same area of contact between 15 the co-operating friction faces is maintained during the movement of the parts relatively to each other, thus greatly reducing the wear of the friction surfaces. By arranging the friction plates so that portions of the friction faces thereof are outside of the housing during the normal position of the parts of the gear, the plates can be arranged farther apart so that more space is available between the plates for insertion of the leaf springs, 20 whereby the capacity of the gear can be increased. The friction faces of the wedge plates and the housing are made relatively long so that the pressure of the springs will be distributed over an extended area and 25 thus reduce the wear of these parts. By arranging the leaf springs as shown in the drawings so that the outer edges thereof bear against the friction plates, the tendency of the plates to rock on the outer edge of the 30 friction face of the housing and thus to bear only on a greatly reduced area, is overcome, thus reducing the wear of these parts.

The wedge plates C and the leaf springs D bear at their inner edges against an intermediate transverse follower or plate E which is movable in the housing lengthwise thereof. The inward movement of the follower in the housing is resisted by a releasing spring contained in the housing between the 35 closed end thereof and said follower. A double coil spring is shown for this purpose, comprising an outer spring F and an inner spring F'. These springs not only assist in resisting the inward movement of the wedge plates in the housing, but also serve to return the wedge plates to their initial or released position after they have been moved inwardly, since the inclination of the friction faces is not great enough to 40 cause them to be returned to their initial position by the leaf springs.

The movement of the coupler in drawing is imparted to the draft gear by means of the usual yoke G extending around the 45 draft gear and connected at its front por-

tion to the rear end g of the shank of a coupler. The rear portion of the yoke extends around a follower H which bears against the projecting outer ends of the wedge plates C and pushes the same inwardly when draft is applied to the coupler. The follower H also co-operates with the rear end of the housing B to form a stop to limit the movement of the wedge plates into the housing and thereby to limit the compression of the springs.

The parts of a draft gear are usually held in operative relation to each other by means of the yoke when the draft gear is installed on a car. It is desirable, however, to construct the draft gear as to hold the parts thereof in operative relation even when the gear is not in place on the car, for example, when the same is being shipped from the manufacturer to the consumer. For this purpose interlocking portions are provided on the wedge plates and the housing to prevent the accidental removal of the wedge plates. In the construction shown, shoulders I are formed on the housing which, in the construction shown, are arranged slightly beyond the inner edges of the inclined friction faces thereof. These shoulders are adapted to engage in recesses I' in the wedge plates which form hooked or shouldered portions i at the inner ends of the wedge plates. The recesses I' are preferably formed at the middle portions of the plates near the inner ends thereof and do not extend completely across the plates, so that the thickness of the plates at the side portions i' is not decreased. This is done to avoid weakening the plates and to avoid breaking of the same by the pressure exerted thereon by the opposite ends of the leaf springs.

Fig. 7 shows a draft gear which is particularly adapted for passenger cars in which the height or vertical dimension of the draft gear is still smaller than in freight cars, for which the gear shown in Fig. 7 is more particularly intended. In this passenger gear two sets of coil springs K K' are shown for resisting the inward movement of the wedge plates. These sets of springs are arranged one beside the other and a follower L is interposed between the two sets of releasing springs and the wedge plates. The releasing springs and the follower are preferably made of such a size that in order to put the releasing springs and the follower L into the housing or remove the same therefrom, it is necessary to construct the housing in two parts. In the construction shown for this purpose the housing comprises a front portion M containing the releasing spring, and a friction housing N secured on the open rear end of the front portion of the housing. The adjacent ends of the two parts of the housing are provided with abutting flanges,

and bolts *n* passing through the flanges connect the two parts of the housing.

O, represents a filler plate which may be of any desired thickness and which is inserted between the two sets of leaf springs. By using filler plates of various thicknesses, one or more spring leaves may be removed from each set of leaf springs so that the capacity of the draft gear can be varied as desired.

In the operation of the draft gear in the drawing, the movement of the yoke forwardly causes the rear follower *H* to move the wedge plates and leaf springs into the housing, which is held against forward movement by the stops *a*. When the forward pressure on the follower *H* is relieved, the releasing springs push the wedge plates and leaf springs back into their initial position. When the draft gear is used in buffing, the housing of the draft gear moves rearwardly toward the follower *H* with the result that the wedge plates and leaf springs again enter the housing, and the action of the other parts of the gear are the same as in drawing.

Draft gears of the constructions described can be made according to the dimensions required by the Master Car Builders' specifications and at the same time have the high capacity required by the railroads. The use of leaf springs between the friction plates is of great importance in connection with the draft gear described, owing to the high resistance offered by the same against bending. The wedge plates are securely retained in the housing, so that the draft gear can be shipped without requiring the parts thereof to be securely held together. By arranging the wedge plates and leaf springs in such a manner that relatively large friction surfaces are in contact at all times, the wear of the draft gear is greatly decreased, thus lengthening the life of the gear.

45 I claim as my invention:

1. In a draft and buffing gear, the combination of a housing having an open end and relatively fixed internal inwardly converging friction faces at said open end, wedge plates slidable into said housing on said friction faces and having friction faces engaging said friction faces of the housing and being movable into said housing, the friction faces of the wedge plates being longer than the friction faces of the housing and extending a considerable distance outwardly beyond the same said wedge plates and friction faces of the housing being so arranged as to cause the wedge plates to move toward each other when the gear is subjected to pressure, and curved leaf springs arranged lengthwise between said plates in oppositely disposed groups with their concave sides facing said plates and their ends bearing on the opposite ends of the wedge plates to oppose the movement of the wedge plates
2. In a draft and buffing gear, the combination of a housing having an open end and relatively fixed internal inwardly converging friction faces at said open end, wedge plates slidable into said housing on said friction faces and having their thick ends extending out of said housing and beyond the friction faces thereof a distance substantially equal to the travel of the wedge plates whereby the area of the friction faces in contact is substantially the same in all positions of the wedge plates, said plates being moved toward each other by said inclined faces, leaf springs arranged lengthwise between said plates to oppose the movement of said plates toward each other, a spring in said housing to oppose the movement of said friction plates into said housing, and cooperating parts on the wedge plates and on said housing which are held in engagement by said leaf springs to hold the plates against movement out of operative relation to the housing, the retaining parts of said wedge plates being formed on the thin portions thereof and reinforcing the same.
3. In a draft and buffing gear, the combination of a housing having an open end and internal inwardly converging friction faces at said open end, wedge plates slidable into said housing on said friction faces and having their thick ends extending out of said housing and beyond the friction faces thereof, said plates being moved toward each other by said inclined faces, leaf springs arranged lengthwise between said plates to oppose the movement of said plates toward each other, a spring in said housing to oppose the movement of said friction plates into said housing, and cooperating shouldered portions formed on said wedge plates and on said housing adjacent to the friction faces thereof, whereby the plates are held against moving entirely out of said housing, the shouldered portions of the wedge plates being formed on the thin portions thereof to reinforce the same.
4. In a draft and buffing gear, the combination of a housing having internal oppositely arranged inclined friction faces, wedge plates slidable into said housing on said friction faces and having their thick ends extending out of said housing and beyond the friction faces thereof, said plates being moved toward each other by said inclined faces, leaf springs arranged between said plates to oppose the movement of said plates toward each other, a spring in said housing to oppose the movement of said friction plates into said housing, said wedge plates having recesses forming shouldered

toward each other the convex face of one set of spring leaves being arranged adjacent to the convex face of another set of spring leaves.

70 2. In a draft and buffing gear, the combination of a housing having an open end and relatively fixed internal inwardly converging friction faces at said open end, wedge plates slidable into said housing on said friction faces and having their thick ends extending out of said housing and beyond the friction faces thereof a distance substantially equal to the travel of the wedge plates whereby the area of the friction faces in contact is substantially the same in all positions of the wedge plates, said plates being moved toward each other by said inclined faces, leaf springs arranged lengthwise between said plates to oppose the movement of said plates toward each other, a spring in said housing to oppose the movement of said friction plates into said housing, and cooperating parts on the wedge plates and on said housing which are held in engagement by said leaf springs to hold the plates against movement out of operative relation to the housing, the retaining parts of said wedge plates being formed on the thin portions thereof and reinforcing the same.

80 3. In a draft and buffing gear, the combination of a housing having an open end and internal inwardly converging friction faces at said open end, wedge plates slidable into said housing on said friction faces and having their thick ends extending out of said housing and beyond the friction faces thereof, said plates being moved toward each other by said inclined faces, leaf springs arranged lengthwise between said plates to oppose the movement of said plates toward each other, a spring in said housing to oppose the movement of said friction plates into said housing, and cooperating shouldered portions formed on said wedge plates and on said housing adjacent to the friction faces thereof, whereby the plates are held against moving entirely out of said housing, the shouldered portions of the wedge plates being formed on the thin portions thereof to reinforce the same.

90 4. In a draft and buffing gear, the combination of a housing having internal oppositely arranged inclined friction faces, wedge plates slidable into said housing on said friction faces and having their thick ends extending out of said housing and beyond the friction faces thereof, said plates being moved toward each other by said inclined faces, leaf springs arranged between said plates to oppose the movement of said plates toward each other, a spring in said housing to oppose the movement of said friction plates into said housing, said wedge plates having recesses forming shouldered

95

portions at the inner ends of the wedge plates, and shoulders on said housing extending into said recesses and adapted to co-operate with the shoulders on said wedge plates to hold the plates against moving entirely out of said housing.

5. In a draft and buffing gear, the combination of a housing having internal oppositely arranged inclined friction faces, wedge plates slidable into said housing on said friction faces and having their thick ends extending out of said housing and beyond the friction faces thereof, said plates being moved toward each other by said inclined faces, leaf springs arranged between said plates to oppose the movement of said plates toward each other, a spring in said housing to oppose the movement of said friction plates into said housing, shouldered portions on said wedge plates at the inner ends thereof, and parts on said housing at the inner ends of said friction faces co-operating with the shouldered portions of the wedge plates to retain said plates in said housing, said parts of the housing having inclined faces forming continuations of the friction faces of said housing.

6. In a draft and buffing gear, the combination of an open ended housing having inwardly converging internal friction faces at its open end, wedge plates slidable into said housing on said friction faces and having their thick ends extending out of the housing beyond the friction faces thereof,

said wedge plates being moved toward each other by said converging friction faces when forced into the housing, leaf springs arranged between said wedge plates to oppose the movement of said plates toward each other, and a releasing spring in the housing for said wedge plates, said wedge plates having strengthening ribs at their inner ends which extend into recesses in the housing.

7. In a draft and buffing gear, the combination of an open ended housing having inwardly-converging internal friction faces at its open end, wedge plates slidable into said housing on said friction faces and having their thick ends extending out of the housing beyond the friction faces thereof, said wedge plates being moved toward each other by said converging friction faces when forced into the housing, leaf springs arranged between said wedge plates to oppose the movement of said plates toward each other, and a releasing spring in the housing for said wedge plates, said wedge plates having longitudinal strengthening ribs at the side edges of their inner ends between which the friction faces of the housing extend.

Witness my hand, this 24th day of March, 1915.

WILLARD F. RICHARDS.
